(57) **CLAIM**

The ornamental design for a base for a medical machine, as shown and described.

DESCRIPTION

FIG. 1 is a top, right side and front perspective view of a base for a medical machine, showing our new design; FIG. 2 is a top, left side and rear perspective view thereof; FIG. 3 is a front elevation view thereof; FIG. 4 is right side elevation view thereof; FIG. 5 is a left side elevation view thereof; and, FIG. 6 is a top plan view thereof. The broken line showing is for illustrative purposes only and forms no part of the claimed design.
